PORTABLE RAFT OR THE LIKE

Raymond D. Berendt, Springfield, Va.

Application July 22, 1959, Serial No. 56,883

Term of patent 14 years

(Cl. D71—1)

Fig. 1 is an isometric view of a portable raft or the like showing my new design;

Fig. 2 is a top plan view of Fig. 1;

Fig. 3 is a side elevational view thereof;

Fig. 4 is an end view of Fig. 1; and

Fig. 5 is a bottom plan view of Fig. 1.

The dominant features of my design reside in the portions shown in full lines.

I claim:

The ornamental design for a portable raft or the like, as shown and described.
